Primary Examiner — T. Chase Nelson*Assistant Examiner* — Mark Cavanna(74) *Attorney, Agent, or Firm* — Brian S. Steinberger; Law Offices of Brian S. Steinberger, P.A.(57) **CLAIM**

The ornamental design for an orthopedic and ergonomic pillow, as shown and described.

DESCRIPTION

FIG. 1 is an upper rear left perspective view of an orthopedic and ergonomic pillow showing my new design.

FIG. 2 is an upper rear right perspective view thereof.

FIG. 3 is an upper front left perspective view thereof.

FIG. 4 is upper front right perspective view thereof.

FIG. 5 is a lower front right perspective view thereof.

FIG. 6 is a lower rear left perspective thereof.

FIG. 7 is a top view thereof.

FIG. 8 is a bottom view thereof.

FIG. 9 is a front side view thereof.

FIG. 10 is a rear side view of the thereof.

FIG. 11 is a left side view thereof.

FIG. 12 is a cross-sectional view of the orthopedic and ergonomic pillow taken along line 12-12 in FIG. 9; and,

FIG. 13 is a cross-sectional view of the orthopedic and ergonomic pillow taken along line 13-13 in FIG. 9.
